Earl G. Watrous,

Attest,

UNITED STATES PATENT OFFICE.

EARL G. WATROUS, OF CHICAGO, ILLINOIS.

LAVATORY-FIXTURE.

1,179,058.

Specification of Letters Patent. Patented Apr. 11, 1916.

Application filed March 7, 1914. Serial No. 823,126.

To all whom it may concern:

Be it known that I, EARL G. WATROUS, a citizen of the United States, residing at Chicago, in the county of Cook and State of Illinois, have invented a certain new and useful Improvement in Lavatory-Fixtures, of which the following is a specification.

My invention relates to lavatory fixtures, such as wash basins and bowls, and has for its object the provision of novel, simple and efficient means for operating the waste plug of the bowl.

In the drawings, Figure 1 is a central vertical section of a bowl to which my invention has been applied; Fig. 2 an elevation of a portion of the casing looking from left to right in the direction of the line of section of Fig. 1; and Fig. 3 a section on the line 3—3 of Fig. 1.

Like letters of reference indicate the same parts in the several figures of the drawing.

My present invention relates more particularly to the manipulating means by which an operating rod, such for instance as that shown in my prior Patent No. 1,016,051, granted to me on January 30, 1912, is operated to shift the waste valve or plug in the bottom of the bowl there shown and described. As there described and as here illustrated the apparatus is suitable for use on railway cars, though applicable to lavatory fixtures generally without regard to the particular use to which they may be put.

Describing briefly the fixtures illustrated in the drawing, the bowl 1 is suitably secured at its bottom to a casing which extends under the drain opening 3 laterally, and is curved upwardly along the portion marked 2 on the drawing through a suitable support 16, and which is provided at its lower end with a combined waste and trap comprising the waste portion 4 and the trap portion 5. The curved portion 2 of the casing (which in the apparatus shown is provided with a connection adapted to communicate with the usual drain of the water cooler of the car) incloses the L-shaped operating rod 6 which rests upon a shoulder 2^a of the casing as a fulcrum, and at its lower end engages the vertically movable waste plug 7 by passing through a slot in the stem thereof. The plug is guided in its movement by means of a lug 8 through which such stem passes.

The construction and arrangement of

parts thus far described is substantially the same as that described in my prior patent above mentioned. By my present invention, however, a tilting or to-and-fro movement is given the upper end of the operating rod 6 by means of novel manipulating means, for the purpose of giving a vertical movement to its lower end and consequently lifting and lowering the waste plug 7 to open and close the drain opening of the bowl. To this end I have provided a tilting operating lever comprising a handle 9, and a lower portion 10 which is globular in shape, which lower portion is provided with opposite trunnions 11 resting in bearing slots formed at opposite sides of the top part of the casing 2. A cap plate or clamp nut 12, having a circular opening conforming to the shape of the globular portion 10 of the lever, permits a limited rocking or tilting movement of the lever upon its trunnions, the opening serving as a stop with which the handle contacts to prevent rocking the lever beyond fixed limits. The spherical surface 80 of the globular part 10, through the center of which the axis of the trunnions passes, completely fills the opening in the cap plate 12 in all positions of the lever. As indicated in the drawings, the lever is constructed as a hollow metal shell and is formed with a slot 13 at its lower end adapted to receive the upper end of the operating rod 6. The upper end of this rod is formed with a groove or slot 14 adapted to 90 engage the lower bend of a compression spring 15, the opposite end of which bears against the upper part of the interior of the globular portion 10 of the operating lever. It is evident that with this arrangement and 95 construction of parts the operating rod 6 will be yieldingly held in either of the two opposite positions to which it may be shifted by the handle, with the waste plug 7 in open or in closed position, as the case may be.

I claim:

1. In a lavatory fixture, a bowl having a drain opening, a vertically movable plug for controlling said opening, a casing comprising a waste passage surrounding the stem 105 of the plug beneath the drain opening and a laterally and upwardly extending curved portion terminating at approximately the level of the top of the bowl and at one side thereof, a rocking lever mounted upon a 110 horizontal pivot or fulcrum at the upper end of said casing and having a vertically

extending handle portion, means for yieldingly holding the lever in its rocked positions on opposite sides of a dead center, and an operating connection between said lever 5 and the plug, extending through and inclosed within said casing, for raising and lowering the plug upon rocking the lever in opposite directions.

2. In a lavatory fixture, a bowl having a drain opening, a vertically movable plug for controlling said opening, a casing comprising a waste passage surrounding the stem of the plug beneath said opening and a laterally and upwardly curved portion terminating at approximately the level of the top of the bowl and at one side thereof, a rocking lever mounted at the upper end of said casing upon a horizontal pivot or fulcrum and having a vertically extending handle portion, an operating connection between said lever and the plug, extending through and inclosed in said casing, for raising and 15 lowering the plug upon rocking the lever in opposite directions, and a spring operating to yieldingly hold the lever in its rocked positions on opposite sides of a dead center.

3. In a lavatory fixture, a bowl having a drain opening, a vertically movable plug for controlling said opening, a casing comprising a waste passage surrounding the stem of the plug beneath the drain opening and a laterally and upwardly extending curved portion terminating at approximately the level of the top of the bowl and 20 at one side thereof, a rocking lever mounted upon a horizontal pivot or fulcrum at the upper end of said casing and having a vertically extending handle portion, an elbow-shaped rod extending through and inclosed 25 within said casing and having the upper end of its vertical portion operatively connected with said lever and the extremity of its horizontal portion operatively connected with the stem of the plug, to cause the rocking 30 of the lever in opposite directions to raise and lower the plug, and a spring operating to yieldingly hold the lever in its rocked positions on opposite sides of a dead center.

5. In a lavatory fixture, a bowl having a drain opening, a plug for controlling said opening, an operating rod for shifting said plug, a rocking lever horizontally pivoted intermediate its length and having its upper end formed as an operating handle and its lower end making slotted engagement with said rod, and a spring interposed between said rod and lever and operating alternatively on opposite sides of a dead 55 center for yieldingly holding said rod in either of its opposite positions.

5. In a lavatory fixture, a bowl having a drain opening, a plug for controlling said opening, an operating rod for shifting said 55 plug, a rocking lever operatively connected

with said rod and having a handle and a curved surface adjacent such handle with its center lying in the axis of oscillation of the handle, and a cap piece having an opening fitting upon said curved surface.

6. In a lavatory fixture, a bowl having a drain opening, a plug for controlling said opening, an operating rod for shifting said plug, a rocking lever operatively connected with said rod and having a handle and a curved surface adjacent such handle with its center lying in the axis of oscillation of the handle, a cap piece having an opening fitting upon said curved surface, and spring tension means for yieldingly holding said operating rod in either of its opposite positions.

7. In a lavatory fixture, a bowl having a drain opening, a plug for controlling said opening, a rocking operating rod for shifting said plug, a hollow rocking lever operatively connected with said rod and having a handle and a curved surface adjacent such handle with its center lying in the axis of oscillation of the handle, a cap piece having an opening fitting upon said curved surface, and a compression spring inclosed in said hollow lever and bearing against said operating rod for yieldingly holding the rod on opposite sides of a dead center in either of its opposite positions.

8. In a lavatory fixture, a bowl having a drain opening, a plug for controlling said opening, an operating rod for shifting said plug, an operating lever pivotally mounted 100 and operatively connected with said rod, said lever having an upper handle portion and a lower spherical portion with its center lying in the axis of the pivotal bearing, and a cap piece having a circular opening 105 fitting upon said spherical portion.

9. In a lavatory fixture having a bowl provided with a drain opening, a vertically movable plug for controlling such opening, a casing connected with the bowl at its outlet and extending upward outside thereof, and a substantially L-shaped operating rod within said casing having its lower end connected with said plug and fulcrumed against its intermediate bend, the outer and upper member of said rod being substantially vertical, means for rocking said rod comprising a rocking lever pivoted adjacent the top end of said rod upon a horizontal pivot or fulcrum and having an upper handle portion 110 and a lower portion making slotted engagement with the top end of the rod, and a spring operating to yieldingly hold the lever on opposite sides of a dead center.

10. In a lavatory fixture having a bowl 125 provided with a drain opening, a vertically movable plug for controlling such opening, a casing connected with the bowl at its outlet and extending upward outside thereof, and a substantially L-shaped operating rod 130

within said casing having its lower end connected with said plug and fulcrumed against its intermediate bend, the outer and upper member of said rod being substantially vertical, means for rocking said rod comprising a rocking lever journaled in the top of the casing upon a horizontal pivot or fulcrum and having an upper handle portion and a lower hollow portion which is slotted on its 10 under side and thereby engages the top end of the rod, and a spring operating to yieldingly hold the lever on opposite sides of a dead center.

11. In a lavatory fixture having a bowl 15 provided with a drain opening, a vertically movable plug for controlling such opening, a casing connected with the bowl at its outlet and extending upward outside thereof, and a substantially L-shaped operating rod 20 within said casing having its lower end connected with said plug and fulcrumed against its intermediate bend, the outer and upper member of said rod being substantially vertical and slotted at its top, means 25 for rocking said rod comprising a rocking lever journaled in the top of the casing and having an upper handle portion and a lower hollow portion which is slotted on its under side and thereby engages the top end of 30 the rod, and a compression spring inclosed in said hollow portion and engaging said slot at the top of the operating rod for 35 yieldingly holding the rod on opposite sides of a dead center in either of its opposite positions.

12. In a lavatory fixture having a bowl 40 provided with a drain opening, a vertically movable plug for controlling such opening, a casing connected with the bowl at its outlet and extending upward outside thereof, and a substantially L-shaped operating rod 45 within said casing having its lower end connected with said plug and fulcrumed against its intermediate bend, the outer and upper

member of said rod being substantially vertical, means for rocking said rod comprising a lever rocking upon trunnions journaled in slots at the top of said casing and having an upper handle portion and a lower hollow curved portion with its center 50 lying in the axis of the trunnions, said hollow portion being slotted on its under side and thereby engaging the top end of the rod, and a cap piece for confining said trunnions in their bearings, said cap piece having 55 an opening fitting upon the curved lower portion of the lever.

13. In a lavatory fixture having a bowl 60 provided with a drain opening, a vertically movable plug for controlling such opening, a casing connected with the bowl at its outlet and extending upward outside thereof, and a substantially L-shaped operating rod 65 within said casing having its lower end connected with said plug and fulcrumed against its intermediate bend, the outer and upper member of said rod being substantially vertical, means for rocking said rod comprising a lever rocking upon trunnions journaled in slots at the top of the casing and having an 70 upper handle portion and a lower hollow spherical portion with its center lying in the axis of the trunnions, said hollow portion being slotted on its under side and thereby engaging the top end of the rod, a compression spring inclosed in said spherical portion 75 of the lever and bearing against said operating rod for yieldingly holding the same in either of its opposite positions, and a cap piece for confining said trunnions in their 80 bearings, said cap piece having a circular opening fitting upon the spherical lower portion of the lever.

EARL G. WATROUS.
